UNITED STATES PATENT OFFICE.

CORINNE MAUDE CLEVELAND, OF NEWTON, MASSACHUSETTS.

MOP.

No. 828,878.

Specification of Letters Patent.

Patented Aug. 21, 1906.

Application filed December 13, 1905. Serial No. 291,559.

To all whom it may concern:

Be it known that I, CORINNE MAUDE CLEVELAND, a citizen of the United States, residing at Newton, in the county of Middlesex and State of Massachusetts, have invented new and useful Improvements in Mops, of which the following is a specification.

This invention has for its object to provide a mop composed of strands or threads of fibrous material disposed in such manner as to form a relatively solid and durable woven neck adapted to be engaged by the clamping members of a mop head or holder and absorbent portions constituting the acting part of the mop, the said absorbent portions being composed of loosely-assembled threads which are extensions of the weft members of the said fabric and extend from opposite ends of the neck formed by said fabric.

The invention consists in the improved mop construction hereinafter described and claimed.

Referring to the drawings, Figure 1 is a plan view of the inside of a mop constructed in accordance with my invention, the same being unfolded or extended. Fig. 2 is an enlarged section taken on line 2 2 of Fig. 1. Like numerals refer to like parts throughout both views of the drawings.

My improved mop comprises elongated parallel threads which are preferably arranged in bunches or strands 5 5. The central portions of the strands 5 5 constitute weft members of a woven fabric which is formed by interweaving with the said central portions warp-threads 7 7. The ends of the warp-threads are extended beyond the edges of the said woven fabric, and with said extended ends are interwoven weft-threads 5' 5', these forming with the extended portions of the warp-threads selvage edges or tabs, which are much thinner than the body portion of the woven fabric, because the weft members of said selvage-tabs are composed of single threads 5', whereas each of the weft members of the body portion of the woven fabric is composed of a bunch of threads forming a strand. The elongation of the strands 5 5 is such that the loose unwoven end portions 6 6 of the strands are considerably longer than the intermediate portions which form the weft members of the fabric, the said unwoven portions 6 6 constituting thick absorbent fringes of ample length pro-

jecting from opposite ends of the woven fabric. After the threads have been assembled, as above described, the selvage edges or tabs are brought together and united by stitches 11 or otherwise, thus converting the woven fabric into a tubular neck which is of double the thickness of the fabric and is adapted to be engaged with the clamping members of a mop head or holder.

It will be seen that the strands 5 5, each composed of a plurality of threads and united at their central portions by the warp-threads 7, constitute a mop the acting portion of which is composed of loose bunches of threads, the bunches being of such bulk and thickness that they constitute an effective mop adapted to absorb large quantities of water and to be freely used without liability of scarring mop-boards, &c. The selvage-tabs forming the edges of the woven fabric enable the fabric portion to be converted into a strong and durable tubular neck, the said tabs also firmly anchoring the end portions of the weft-threads and preventing any possibility of the raveling of the fabric.

I have shown rows of stitching 9 9 extending transversely across the mop between the ends of the woven portion and the outer ends of the strands 5. These stitches are not essential, however, and may be omitted.

I claim—

A mop comprising elongated parallel threads arranged in bunches or strands, warp-threads interwoven with the central portions of the strands and forming therewith a woven fabric, of which the central portions of the strands constitute the weft members, and weft-threads parallel with the strands and interwoven with the end portions of the warp-threads to form selvage edges or tabs on said fabric, the said tabs being brought together and united to convert the woven fabric into a mop-holder engaging tubular neck, from the opposite ends of which the free or unwoven end portions of said strands extend and form the acting portion of the mop.

In testimony whereof I have hereunto set my hand in presence of two subscribing witnesses.

CORINNE MAUDE CLEVELAND.
